CLAIM

I claim the ornamental design for a bra, as shown and described.

DESCRIPTION

FIG. 1 is a front, left perspective view of a bra, showing my new design;

FIG. 2 is a front view thereof;

FIG. 3 is a front, right perspective view thereof;

FIG. 4 is a left side view thereof; and,

FIG. 5 is a right side view thereof.

The dot-dot-dash broken lines represent unclaimed boundaries of the claimed design. The broken lines depicting the remainder of the bra show features that form no part of the claimed design.
